UNITED STATES PATENT OFFICE.

HARRY T. KINGSBURY, OF KEENE, NEW HAMPSHIRE.

SELF-PROPELLED TOY VEHICLE.

1,144,850.

Specification of Letters Patent.

Patented June 29, 1915.

Application filed May 8, 1913. Serial No. 766,333.

To all whom it may concern:

Be it known that I, HARRY T. KINGSBURY, a citizen of the United States, residing at Keene, in the county of Cheshire, State of New Hampshire, have invented certain new and useful Improvements in Self-Propelled Toy Vehicles, of which the following is a description, reference being had to the accompanying drawing and to the figures of reference marked thereon.

My invention relates to improvements in self-propelled toy vehicles.

The object of my invention is to provide a wheeled toy in which the motor and winding crank are readily connected, the winding crank being at the forward end of the vehicle, as now employed on all motor vehicles.

Another object of my invention is to provide a structure whereby the winding crank and its ratchet carried thereby do not have to be accurately positioned, whereby a slight difference in the length of the body of the toy will not prevent the same from being readily applied in an operative position.

A still further object of my invention is to provide a simple, cheap and effective toy of this character, which may be easily assembled.

The invention, therefore, consists in the matters hereinafter described and referred to in the appended claims.

In the accompanying drawings, Figure 1 is a perspective view of a toy automobile embodying my invention; Fig. 2 is a vertical longitudinal sectional view; Fig. 3 is a rear end view; Fig. 4 is a bottom plan view; Fig. 5 is an inverted perspective view of the forward end of the hood of the machine, looking from the rear, and showing the ratchet mechanism for holding the crank against rotation; Fig. 6 is a bottom plan view of a modified form of winding crank and the motor spring connection. Fig. 7 is a detail view showing the structure of the ratchet wheel.

Referring now to the drawings, 1 represents the body of the automobile, which may be of any desired form. The said body is provided at the rear with downwardly extending lugs or ears 2 and 3, in which is rotatably mounted the rear axle 4 carrying the drive wheels 5 and 6. The forward end of the body has pivoted to the under side thereof at 7, a bar or plate 7, extending beyond the sides of the body and having down-

wardly extending ears or lugs 8 and 9 carrying the forward axle 10, on which are rotatably mounted the forward wheels 11 and 12. By pivoting the bar or plate 7, it will be seen that the forward axle is turned so that the toy can be set so that it will travel straight or in a circle. The pivot 7 is very tight, so that the bar or plate 7 will retain any position in which it is adjusted, this being caused by friction.

The forward end 13 of the body 1 of the car is provided with an opening 14, through which the winding crank 15 extends. The said crank extends longitudinally of the vehicle and has its rear end extending through the gear case 16, supported by ears 17 and 18 on the rear axle 4. This gear case has an extension 19, extending through an opening 20 in the body of the car, which prevents the casing from rocking on the axle.

Carried by the crank 15 within the gear casing is an enlarged gear 22', meshing with a pinion 22 keyed upon the rear axle 4, whereby the rear axle is driven. The front side of the gear case has an enlarged opening, and rigidly carried by the crank within the opening is an elongated sleeve 23 having at its forward end an annular flange 24. This flange is in the form of a disk having openings through which extend ears 25, carried by the sleeve and by means of which the disk is locked to the sleeve. The forward disk is locked or held fast upon the winding crank by being pressed on to form 90 projecting lips smashed out on the crank. Surrounding the sleeve 23 is a coiled spring 26, which has one end secured to the flange 24 by means of the openings 27, the opposite end of the spring being secured to the ear 28 struck out from the metal of the drive gear 22', and whereby the gear will be rotated by the spring.

The forward end of the crank, as heretofore stated, passes through an opening in the body or front of the car, and has a squared portion 29, shown in Fig. 5. Carried by the crank on the inside of the front of the body, is a ratchet with teeth 31, said ratchet having a round opening 30 of a size 105 to allow the crank to be readily passed therethrough, and having notches 30' on opposite sides in which the squared portion of the crank passes, whereby the ratchet is held against rotation on the crank. Surrounding 110 the crank is a dog 32, having an elongated opening, through which the crank passes,

whereby the dog has a horizontal sliding movement independent of the crank. This dog, as shown, is made of a flat plate having lateral ears 33 and 34 at opposite sides, 5 which have the outwardly extending portions 35 and 36. The lower ends of said outwardly extending portions 35 and 36 have upwardly turned ends 37 and 38 which extend through horizontal elongated slots 39 10 and 40 in the front of the body, which slots are considerably longer than the width of the turned ends 37 and 38, whereby the dog has a free horizontal movement. This distance between the outwardly turned portions 15 37 and 38 is slightly less than the greatest diameter of the ratchet, whereby when the ratchet is rotated, the teeth engage the same and cause a reciprocation of the dog. The teeth on the ratchet are so arranged that but 20 one engages the dog at a time, and the teeth on opposite sides, therefore, cause the dog to move first in one direction and then the other. The dog is at all times in such a position that one of the portions 37 or 38 is in beyond 25 the teeth thereof, whereby the backward tension of the spring on the crank, when released, causes the square portion of the tooth to lock against the dog, and prevents its backward rotation.

30 In the modification shown in Fig. 6, instead of having a sleeve, I mount the coiled spring directly on the crank, one end being secured to a lug 41, carried by the crank, and the opposite end being connected to the ear 35 42, carried by the drive gear 43. In this form, I have shown only a frame 44 for supporting the gear, and not a case entirely inclosing the same.

In operation, the crank is rotated to the 40 right, as is usual in winding a spring, and the rear wheels are held or the vehicle itself held upon the floor with a little pressure. The rotation of the crank causes the spring to coil upon the sleeve or crank. As heretofore stated, when the crank is released, the dog holds it against backward rotation. The vehicle is then released, and the rear 45 end of the spring being connected directly to the drive gear, the same is set in motion by the uncoiling of the spring, and through the medium of the pinion the rear axle is rotated very rapidly and the vehicle set in motion.

Having thus described my invention, what 50 I claim as new and desire to secure by Letters Patent, is:

1. A self-propelled toy comprising a body portion, a rear axle, supporting wheel rigidly carried by the axle, forward supporting wheels, a 55 crank rotatably mounted in the forward end of the body portion, and extending adjacent the rear axle, a gear loosely mounted on the rear end of the crank, a pinion carried by the rear axle and meshing with the gear, a 60 spiral spring surrounding the rear end of

the crank and having one end secured thereto and the opposite end secured to the gear, and a ratchet carried by the crank at the forward end of the body and longitudinally movable thereon, and a pawl carried by the 70 body portion and engaging the ratchet.

2. A self-propelled toy comprising a body portion, a rear axle, supporting wheels rigidly carried by the axle, forward supporting wheels carried by the body, a crank on the outside of the forward end of the body and extending adjacent the rear axle, a spiral spring on said crank for rotating the rear axle, the forward end of the crank having a 75 rectangular portion, a ratchet having a corresponding opening to receive the crank longitudinally movable thereon, and a pawl carried by the body and engaging the ratchet.

3. A self-propelled toy comprising a body portion, a rear axle, supporting wheels carried thereby, forward supporting wheels, a crank extending from the forward end of the body to the drive wheel, a spring secured to the crank and adapted to drive the 85 rear axle, a ratchet carried by the forward end of the crank longitudinally movable thereon on the inside of the body, a pawl slidably supported by the body and surrounding the crank and adapted to engage 90 the opposite sides of the ratchet.

4. A self-propelled toy comprising a body portion, a rear axle, wheels carried thereby, forward wheels, a crank extending through the front of the body portion and extending adjacent the rear axle, a spring secured to the crank and adapted to drive the rear axle, a ratchet longitudinally movable on the crank on the inside of the body portion but held against rotation, a pawl horizontally 105 slidably mounted in the body portion and holding the ratchet between it and the body portion and surrounding the shaft and adapted to engage the opposite sides of the ratchet, whereby the crank may be operated 110 in one direction.

5. A self-propelled toy comprising a body portion, a rear drive axle and wheels, forward wheels, a crank passing through the front of the body portion and extending adjacent the rear axle, a spring connected to the crank and adapted to drive the rear axle, a ratchet movable on the crank but held against rotation, a plate on the inside of the ratchet and having a slot through which 120 the crank passes, outwardly extending pawls carried by the plate on opposite sides of the ratchet and horizontally movably supported in the body portion and adapted to engage 125 the opposite sides of the ratchet.

6. A self-propelled toy comprising a body portion, a rear axle and wheels, forward wheels, a crank passing through the front of the body portion, a spring connected to the crank and adapted to rotate the drive axle, 130

5 said crank having a flattened portion, a ratchet having a round opening through which the crank passes, and notches to receive the flattened portion of the crank, a plate 10 on the inside of the ratchet and having a horizontal slot through which the crank passes, outwardly extending arms carried by the plate having pawls spaced apart a distance slightly less than the diameter of the ratchet, and the forward end of said pawls 15 passing through elongated slots in the front of the body portion and turned at right angles to the slot, whereby the pawls and plate have a horizontal movement.

20 7. A self propelled toy comprising a body portion, a rear drive axle and wheels, forward wheels, a crank passing through the front of the body portion and extending adjacent the rear axle, a spring connected to the crank and adapted to drive the rear axle, a ratchet longitudinally movable on the crank but held against rotation, and a plate 25 movably connected to the body portion and having pawls on opposite sides of the ratchet

and adapted to engage opposite sides of the ratchet.

8. A self propelled toy comprising a body portion, a rear drive axle and wheels, forward wheels, a crank passing through the front of the body portion and extending adjacent the rear axle, a spring connected to the crank and adapted to drive the rear axle, a ratchet longitudinally movable on the crank but held against rotation, and a plate 30 movably supported by the forward end of the body portion and having outwardly extending pawls on opposite sides of the ratchet and spaced apart a distance slightly less than the diameter of the ratchet and whereby the pawls and plate have a horizontal movement.

In testimony whereof, I affix my signature in the presence of two witnesses.
